UNITED STATES PATENT OFFICE.

ERNEST M. JOHNSON, OF JERSEY CITY, NEW JERSEY, ASSIGNOR TO EDWARD V. HARTFORD, OF DEAL, NEW JERSEY; HENRIETTA POLLITZER HARTFORD ADMINISTRATRIX OF SAID EDWARD V. HARTFORD, DECEASED.

GOVERNOR.

Application filed July 14, 1920. Serial No. 396,218.

In all governor design the speed and closeness of regulation at that speed are assumed quantities, and from these quantities, and others, the details are worked out. In all 5 the governors heretofore known to me, the closeness of regulation varies in some fashion with the speed. That is, the usual mechanism which is satisfactory for one predetermined speed is entirely unsuited for another 10 speed, by reason of the fact that centrifugal forces vary with the square of the speed, at a constant radius of gyration. On account of this, it has been difficult to regulate the 15 speed of variable speed machinery to a satisfactory degree.

One of the objects of my invention is to provide a governor which is capable of close regulation of the speed of variable speed machinery, more particularly one in which 20 the closeness of regulation of speed, throughout a long range in speed, is, for all practical purposes, independent of the speed.

Another object of my invention is the provision, in a close regulating governor, of one 25 or more of the following features: (1) adjustability of speed while running, (2) low energy consumption in the sustaining of the governor parts in position, (3) minimum wear of parts, (4) accessibility for inspection, (5) a natural period far above any speed likely to be attained.

Another object of my invention is to provide instrumentalities which may be utilized to transmit to an external medium the disturbances set up by the governor whenever 35 the speed falls below or exceeds that for which it is set, so that an energy supply may be controlled. In the embodiment set forth in the drawings an electric switch is shown, 40 to control the energy supply of a motor.

Other objects of my invention will appear as the description of the illustrated embodiment of my invention shown in the drawings 45 proceeds, and I desire it to be understood that the specific description of my invention is intended as illustrative rather than limiting the invention.

In the drawings:

Fig. 1 is an elevation, with the cover removed, of a governor made in accordance 50 with my invention, showing it in connection with an electric motor and a switch.

Fig. 2 is a section on the line 2—2 of Fig. 1; and

Fig. 3 shows the characteristic curves for a 55 typical governor.

The governor is shown as being driven from the left end 37 of the shaft of a series electric motor whose armature and field are diagrammatically represented at 18 and 19. 60 The motor is supplied from mains 20 and 21 through a relay 22 whose coil 23 is connected by a lead 25 to a movable contact 28. This contact cooperates with a fixed contact 27 connected by lead 26 to the other side of 65 the line. The break may be shunted by a resistance and capacity 24.

An under-frame 29 having an annular end 30 is bolted securely to the end-frame of the motor. The under-frame 29 has two up-standing lugs or posts 32 and 33. The frame is longer at the rear than at the front, and the longer portion 34 is provided with a bearing 35 integral therewith for a control-screw 36 which is connected to a hand-wheel 70 75 15. The outer surface 35' of this bearing is machined to take the thrust of a spring connected to the control-screw.

The left end 37 of the armature shaft extends beyond the end-frame of the motor and 80 has a diametral slot or groove 38 cut therein. This slot or groove is adapted to receive an outwardly extending tongue from an element connected to drive the governor shaft.

On the post 32 is mounted a bearing-housing 39 which supports a ball-bearing 40. The bearing 40 is held in position by the end-part 41, which is grooved at 42, in order 85 to retain lubricant in the bearing. The housing 39 is also grooved as at 43 to retain 90 lubricant in place. The lubricant may be supplied from the grease-cup 44 through the tube 45. The bearing-housing may be definitely located on the post 32 and aligned 95 by means of dowel-pins, as 46, and shoulders, 47.

The lug or post 33 on the frame 29 supports another bearing-housing 48 which is held firmly in place by suitable bolts 49, dowel-pins 50 and shoulders 51. The housing 48, at the left, supports a ball-bearing 52. This bearing is held in place by an end-plate 53, provided with a lubricant retaining groove 54. The housing 48 also supports a 100

thrust-bearing 55, the housing in this case extending to the right far enough to inclose the bearing, where it is provided with a lubricant retaining groove 56. The lubricant 5 may be supplied by means of grease cup 44' through the tube 45'.

The bearings 40 and 52 support a shaft 57 on which are mounted the rotating governor parts. The right hand end of the 10 shaft 57 is shouldered at 58 to receive the bearing 40 and is threaded at 59 to receive the threaded end 60 of a member 61 which has integral thereto a tongue 62 for engagement in the slot 38 in the motor shaft 37. 15 The member 60 is pinned to shaft 57 at 60', and clamps the inner member of bearing 40 against shoulder 58.

The other end of the shaft 57 is shouldered at 64 to receive the bearing 52. The shaft is 20 shouldered at 65 and threaded at 66 to receive a nut 67 which is adapted to clamp the inner member of the bearing 52 in place.

The shaft 57 has a long key 68, fixed to it. 25 All of the rotating elements of the governor, to be described, are driven through this key and are adapted to slide on the key, to a limited extent. At the left, the hub 69 of spider-shaped member 70 is mounted. The hub 69 is shouldered at 71 where it fits the 30 thrust-bearing 55. The spider-shaped member 70 has four arms, two of which, 72 and 73, are adapted to drive one set of centrifugal elements, the other two of which, 74 and 75, are adapted to drive another set of centrifugal elements. The arms 72 and 73 are each bifurcated at 76 and 77 and a hardened 35 steel shaft 78 having a knife edge 79, is supported by these bifurcations. The arms 74 and 75 are similarly provided with bifurcations 80 which extend to the dotted lines 81 and 82. Steel shafts 83, knife-edged at 84, are supported within the bifurcations 80.

A long sleeve 85 is supported on the shaft 57 and adapted to slide on key 68. This 40 sleeve has an annular shoulder 86 to receive the thrust of a small helical spring 87. The other end of this sleeve is threaded as shown and shouldered at 89. The intermediate portion of this sleeve is provided with two keys 90 and 91, fixed thereto on which another sleeve 92 is adapted to slide. The end of the latter sleeve abuts against the other end of the spring 87. A 45 collar 93 is threaded on the sleeve 85 and one part 94 of a ball-bearing 95 is mounted on the shouldered end 89 of this sleeve.

The arms 72 and 73 of the spider 70 carry, 50 by means of the knife-edged shafts 79, two bell-crank members 96 having short arms 97. The sleeve 85 is cut away at 85' to provide shoulders 86' against which rollers 98 on arms 97 abut. The other arms 99 of the bell-cranks 96 are provided with weights or 55 balls 100. These weights, when the governor is idle, are held against the outside of

a flange 101 on sleeve 92, by a spring to be described.

The arms 74 and 75 of the member 70 carry, on the knife-edged shafts 83, bell-crank members 102. Each of the members 70 102 supports on its arms 103 a ball or weight 104. Each of the other arms 105 of the bell-crank members 102 has a pivot-pin 106 on which one end of a connecting member 107 is mounted. The sleeve 92 has two outstanding 75 oppositely disposed bifurcated ears 108, which carry pivot pins 109. The other end of each of the connecting members 107 is connected to one of the pins 109. When at rest the spring 87 will hold the arms 103 80 next the bottom wall 81 of the bifurcations 80. At this time there is a slight clearance, two small to appear on the drawing, between sleeve 92 and collar 93.

An annular housing 110 having the cross-section shown in Fig. 2, is provided for the thrust-bearing 95, and has a grease-cup 111, lubricant retaining grooves 112 and two knife-edged members one of which is clearly 85 shown at 113 in Fig. 1. These knife-edged 90 members are fastened to the outside wall of the housing on opposite sides of the central opening through which the shaft 57 passes.

The bearing 35 for the control-screw 36 is 95 provided with a small inwardly extending pin 115, which cooperates with the groove 116 on the screw 36 to retain the screw in place. The major portion of this screw is 100 threaded as shown at 117. The free end of the screw is provided with a nut 118. This 105 nut is guided by means of a member 119 connected to a pointer 16, which slides in a slot 16' in the cover 14 and by a second member (not shown) adapted to slide in a groove 118" in the under-frame 29.

One end of a comparatively large spring 119' fits over the nut 118, and the other end of this spring is provided with a hook 120 to cooperate with an eye 121. The eye 121 is 110 suitably connected to a knife-edged member 122 which rests in a notch 123 in a balancing lever 124. This lever is provided with a notch 125 intermediate its ends, which notch is adapted to receive the knife edged members 113 and 114. The other end of the lever 115 124 is notched as at 126 to cooperate with a vertical knife-edged member 127, supported on a post 127' carried by the under frame 29. The lever 124 is shown in section in Fig. 2, and is provided with an aperture 128 somewhat larger than the shaft 57 which 120 passes therethrough.

The bearing-housing 39 supports on the top thereof a slab 129 of insulating material 125 on which are mounted the switch contacts 27 and 28 and mechanism for operating same from an arm 130, attached to a post 130' which is in turn supported by the lever 124. The arm 130 is connected to the short bifurcated arm 131 of a bell-crank member. The 130

longer arm 132 of this bell-crank member is provided at its free end with a T-head having downwardly bent ends on which are mounted screws 135, adapted to be locked in place by lock-nuts 136. The bell-crank member is pivoted at 137 on a fixed member 138 which is also provided with a horizontal grooved pin 139.

Intermediate the ends of the arm 132 there is supported on the slab 129 a C-shaped member 149, carrying a knife-pivot equipment, indicated in broken lines in Fig. 1, near the terminus 149' of the upper or crown curve of the C. One of such pivots is carried by the underside of said crown curve of the C, and the other by the upper side of the bottom curve of the C; the pivots being vertically aligned. A member 156 is mounted as a lever on these bearings. This member, which is also shown in Fig. 1, being there shown only in top plan; but being a U-shaped member in side elevation, so that the legs of the U, one vertically above the other, have their free ends presented in the vicinity 25 of said knife-pivots for attachment thereto to give the member 156 its lever mounting. The lower leg of the member 156 is located in the plane of the screws 135, carried by the down bent ends of the T-head of arm 132 of the bell-crank lever. A spring 159 is fastened to the central portion of the U-shaped member 156 and hooked in the groove of post 139. This spring will bias the member 156 to one side or to the other side of its 30 knife-pivot mounting. The member 156 is held to a limited range of movement by means of adjustable stops 160 and 161. The central portion of the U-shaped member 156 has fastened on each side thereof the Z-pieces 162 and 163, thereby providing bifurcations. The outer end of each of these Z-shaped members 162 and 163 is provided with adjustable stops as shown.

The movable switch contact 28 is pivoted on knife-edged members indicated in broken lines in Fig. 1, and supported in a member 174 similar in shape to 149 and in a fashion similar to the U-shaped member 156. A part of the contact 28 is between the ends of the stops on Z-pieces 162 and 163. The switch 28 is biased to one side or to the other side of its knife-pivots by means of a spring 171 connected to the central part of the switch member and to a post 172 carried on the insulating slab 129. A suitable binding post 173 is connected to the C-shaped member 174 which supports the switch element. The other binding post 175 for supporting the fixed contact is provided with means to adjust the position of the fixed contact. In this case a screw 176 provided with a suitable lock nut is employed. The extent of movement of the switch element 28 in the opposite direction is limited by means of an 45 adjustable stop 178 similar to the afore-de-

scribed means except that it is not electrical- ly connected to a lead.

The cover 14 which is over the governor and switch, is fastened in place by suitable means not shown. This cover is provided with a removable plug 180 to afford access to grease cup 111, without necessitating the removal of the cover.

The adjustment of the speed at which the governor will control the motor is made by means of the hand-wheel 15. By this hand-wheel the member 118 can be moved to the left or right, thereby adjusting the tension under which the spring 119' is to be placed.

The pull developed in the spring 119' is transmitted by means of the lever 124 to the knife-edges 113, carried on the housing 110. The housing 110 floats on the bearing 95 carried on the sleeve 85 on shaft 57. The force transmitted from the lever 124 to this housing, on account of the symmetry of the device, becomes an axial thrust through the housing 110, bearing 95, sleeve 85, shoulders 86', rollers 98, bell-crank member 96, knife-edged shafts 78, spider-shaped member 70, and thrust bearing 55, which abuts the fixed bearing-housing 48, carried rigidly by the under frame 29. The balls 100 are held upon the flange 101 of sleeve 92, by this thrust when the governor is at rest.

According to the design of this governor, the balls 104 are free to move about their pivots and assume a position which will depend upon the speed at which the device is operating and the characteristics of spring 87, but not upon the pull developed in spring 119'. The balls 104 as they move back and forth will operate against the spring 87 in a fashion similar to the ordinary fly-ball governor. When at rest the spring 87 merely reacts against the flange 86 and the sleeve 92. When the spring 87 is compressed, owing to the centrifugal forces developed in the balls 104, its reaction toward the left is taken up by flange 86, bell-cranks 96, pivot-shafts 78, and spider-shaped member 70. Its reaction toward the right is taken up by sleeve 92, connecting links 107, bell-cranks 102, pivot members 83, supported by spider-shaped member 70.

The centrifugal forces developed by the balls 100, act against the shoulder 86' on sleeve 85, and in order for these balls to move away from the flange 101, they must develop sufficient force not only to overcome the thrust transmitted to the sleeve 85 from the spring 119' but also to overcome the reaction of spring 87 against the flange 86, and, moreover, the amount of force which is to be developed by this latter spring will depend upon the position in which the free balls 104 are. It is thus apparent that while the balls 104 and the parts they operate are free to assume a position depending upon the speed at which the governor is driven,

yet the balls 100 which may be termed the restrained balls, are not able to move away from the axis and assume a position determined solely by the centrifugal force developed and the tension of the spring 119'.

It is well known that the centrifugal force developed by a mass varies directly with the radius of gyration and with the square of the speed. If a plot is made showing the 10 centrifugal force obtained at various speeds at a constant radius of gyration a parabola will be obtained. Since the centrifugal force developed is a function of both the radius of gyration and the square of the speed, the 15 curve to be obtained by plotting the centrifugal force against the speed, where the governor balls are permitted to fly outwardly so that the radius of gyration increases with the speeds is not a true parabola but it indicates that the centrifugal force increases at 20 a different rate.

The balls 100, whose radii of gyration are substantially invariable, for reasons to be pointed out, develop centrifugal forces which 25 vary with the square of the speed, i. e., substantially parabolically.

In the governor shown in the drawings the free balls 104 with their connecting parts constitute a simple governor whose characteristic curve is of the type last described. The design and proportion of the parts is made so that the thrust developed in the 30 spring 87 by the free balls 104 opposes the centrifugal force developed by the balls 100.

The centrifugal force developed by the balls 100 acts through the rollers 98 upon the flange 86' of the sleeve 85 and thence in an obvious manner to the lever 124 and opposes the pull exerted by the spring 119'. As 35 before pointed out, the amount of tension in the spring 119' can be regulated by the hand wheel 15. Hence it appears that by increasing tension in the spring 119' the balls 100 may be urged inwardly more strongly. It is 40 also apparent that the operation of the free balls 104 and the parts they move, is directly opposed to the operation of the restrained balls 100 and the parts they move.

The resultant or cumulative centrifugal 45 force to be developed by the combined devices will be the difference between that developed by the balls 100 and that developed by the balls 104. This is represented in Fig. 3 by a plot. The curve A is a parabola representing the centrifugal force developed by the fixed or restrained balls 100, the curve B represents the characteristic performance of the free balls 104 and parts operated thereby. When the curve B is subtracted from 50 the curve A, the characteristic curve C for the composite governor is obtained.

The more closely the curve C approximates a straight line, the more nearly constant will be the absolute regulation of motor-speed by the governor. The matter of 55

securing a straight line for the curve C is one of design and may be obtained by carefully computing the centrifugal forces developed by all the parts of the governor in their various positions and at corresponding speeds and the forces necessary to deform the springs. In practice the design can be made such, for example, that if the governor regulates to within 50 revolutions per minute at 1,000 revolutions per minute, 70 it will regulate to within about 52 to 55 revolutions per minute at 5,000 revolutions per minute. As a practical matter, the designer should not attempt to make the line C absolutely straight because then, there might 75 possibly occur points of inflection in this line which would indicate that the governor was unstable at some particular or critical speeds.

In order to control the energy supply to 80 the motor from such a sensitive governor, a very delicate switch is provided in the relay circuit. The switch is operated by the arm 130 connected with the lever 124. The arm 130 operates a bell-crank the long arm 85 132 of which carries as above described the adjustable stops 135. This bell-crank arm will move back and forth in accordance with the movements imparted to the lever 124 by the balls 100 which when the motor is 90 running are a slight distance from the flange 101. They must move, however, a finite distance before the stops 135 will touch the lower portion of the U-shaped member 156 and force said member past dead-center, so 95 that the coiled spring 159 will snap the member 156 quickly against the limiting stop. The member 156 does not itself make electrical contact to open or close the circuit, but it is provided with adjustable stops on 100 its Z-pieces 162 and 163 which engage with the tongue on the movable switch element 28 to pull it to one side or the other side of dead center so that the spring 171 can snap it either away from the fixed contact 27 of 105 the switch or against the fixed stop 178. The delicate mechanism above described will not stick at any point nor can it flutter. It either makes a good contact or a clear break.

In the operation of the governor, the 110 switch already described will be open at all times when the speed is in excess of that determined by the setting of the tension of the spring 119'. As soon as the speed drops below that, the over-powering action of the 115 balls 104 is removed, and the balls 100 can then fly out a slight distance and thereby operate the mechanism to close the switch. The closing operation is similar to the opening operation above described.

It is thus apparent that the difference between the forces developed by the composite governor at a speed of X and at a speed of $X - \alpha$ will be all that is available to 120 operate the switch. The distance through 125

which this useful force moves will also be very small. It is in fact determined by the build-up of the spring 119' necessary to sustain the increment in centrifugal force developed by the governor. The switch above shown has been designed to be operated by a mass of 200 grams operating through a distance of 1.5 mm.

While the mechanical movement operated by the governor for controlling energy supply is in the present embodiment an electric switch, I would have it understood that other instrumentalities may be employed, as for example, valve ports may be opened or closed.

I claim:

1. In combination, two sets of centrifugal elements each mounted to have a variable radius of gyration, and means associated with each set of elements to oppose increase in the radius of gyration thereof, each means controlling yielding elements and being susceptible of adjustment during the operation of the governor.

2. In combination, two sets of centrifugal elements each mounted to have a variable radius of gyration, and yielding means associated with each set of elements to oppose increase in the radius of gyration thereof, each means controlling yielding elements and being susceptible of adjustment during the operation of the governor.

3. In combination, two sets of centrifugal elements each mounted to have a variable radius of gyration, and spring means associated with each set of elements to oppose increase in the radius of gyration thereof, each means controlling yielding elements and being susceptible of adjustment during the operation of the governor.

4. In combination, two sets of centrifugal elements each mounted on a common support to have a variable radius of gyration, and means associated with each set of elements to oppose increase in the radius of gyration thereof, each means controlling yielding elements and being susceptible of adjustment during the operation of the governor.

5. In combination, two sets of centrifugal elements each mounted to have a variable radius of gyration, means associated with each set of elements to oppose increase in the radius of gyration thereof, and means to vary one of the aforesaid means while the governor is operating.

6. In combination, two sets of centrifugal elements each mounted to have a variable radius of gyration, yielding means associated with each set of elements to oppose increase in the radius of gyration thereof, and means to vary one of the aforesaid means while the governor is operating.

7. In combination, two sets of centrifugal elements each mounted to have a variable

radius of gyration, spring means associated with each set of elements to oppose increase in the radius of gyration thereof, and means to vary one of the aforesaid means while the governor is operating.

8. In combination, two sets of centrifugal elements each mounted on a common support to have a variable radius of gyration, spring means associated with each set of elements to oppose increase in the radius of gyration thereof, and means to vary one of the aforesaid means while the governor is operating.

9. In combination, a first set of centrifugal elements mounted to have a variable radius of gyration, a second set of centrifugal elements similarly mounted, means opposing an increase in the radius of gyration of the first set, means independent of the first means for opposing an increase in the radius of gyration in the second set, and means to transmit the opposition set up by the first means to the second set of centrifugal elements to thereby oppose an increase in the radius of gyration thereof, the parts being so arranged as to be susceptible of adjustment while the governor is operating.

10. In combination, a first set of centrifugal elements mounted to have a variable radius of gyration, a second set of centrifugal elements similarly mounted, spring means opposing an increase in the radius of gyration of the first set, spring means independent of the first means for opposing an increase in the radius of gyration in the second set, and means to transmit the opposition set up by the first means to the second set of centrifugal elements to thereby oppose an increase in the radius of gyration thereof, the parts being so arranged as to be susceptible of adjustment while the governor is operating.

11. In combination, a first set of centrifugal elements mounted to have a variable radius of gyration, a second set of centrifugal elements similarly mounted, means opposing an increase in the radius of gyration of the first set, means opposing an increase in the radius in the second set, means to transmit the opposition set up by the first means to the second set of centrifugal elements to thereby oppose an increase in the radius of gyration thereof, and means to vary the opposition set up by the second means.

12. In combination, a first set of centrifugal elements mounted to have a variable radius of gyration, a second set of centrifugal elements similarly mounted, spring means opposing an increase in the radius of gyration of the first set, spring means opposing an increase in the radius of gyration in the second set, means to transmit the opposition set up by the first means to the second set of centrifugal elements to thereby oppose an increase in the radius of gyration thereof,

and means to vary the opposition set up by the second spring means while the governor is in operation.

13. In a variable speed governor, two sets of centrifugal elements each mounted to have a variable radius of gyration, means associated with each set of elements to oppose an increase in the radius of gyration thereof, means to vary the opposition of one of the aforesaid means, and means to algebraically summate the forces developed centrifugally whereby a speed-centrifugal force characteristic may be secured which differs from that of each set of elements while the governor is in operation.

14. In a variable speed governor, two sets of centrifugal elements each mounted to have a variable radius of gyration, yielding means associated with each set of elements to oppose an increase in the radius of gyration thereof, means to vary the opposition of one of the aforesaid yielding means, and means to algebraically summate the forces developed centrifugally whereby a speed-centrifugal force characteristic may be secured which differs from that of each set of elements while the governor is in operation.

15. In a variable speed governor, two sets of centrifugal elements each mounted to have a variable radius of gyration, a spring associated with each set of elements to oppose an increase in the radius of gyration thereof, means to vary the opposition of one of the aforesaid springs, and means to algebraically summate the forces developed centrifugally whereby a speed-centrifugal force characteristic may be secured which differs from that of each set of elements while the governor is in operation.

16. In a variable speed governor, two sets of centrifugal elements each mounted on a common support to have a variable radius of gyration, a spring associated with each set of elements to oppose an increase in the radius of gyration thereof, means to vary the opposition of one of the aforesaid springs, and means to transmit the sum of the centrifugal forces whereby a speed-centrifugal force characteristic may be secured which differs from that of each set of elements while the governor is in operation.

17. In a governor; a shaft; a sleeve slidably mounted thereon; a spring opposing the movement of the sleeve in one direction; means to adjust the tension in the spring; a first set of centrifugal elements opposing the movement in the opposite direction; and means to restrict the movement of said first set of centrifugal elements at all speeds below the speed corresponding to the tension in the spring, said last mentioned means comprising a second set of centrifugal elements and opposing means therefor to permit the radius of gyration thereof to increase

with the speed, the parts being so arranged as to be susceptible of adjustment while the governor is operating.

18. In a governor; a shaft; a sleeve slidably mounted thereon; a spring opposing the movement of the sleeve in one direction; means to adjust the tension in the spring; a first set of centrifugal elements opposing the movement in the opposite direction; and means to restrict the movement of said first set of centrifugal elements at all speeds below the speed corresponding to the tension in the spring, said last mentioned means comprising a second sleeve on the first sleeve, a second spring intermediate the second sleeve and the first sleeve, and a second set of centrifugal elements associated with the second sleeve to compress the second spring with increase in speed.

19. In a governor; a shaft, a sleeve slidably mounted thereon; a spring opposing the movement of the sleeve in one direction; means to adjust the tension in the spring; a first set of centrifugal elements opposing the movement in the opposite direction; means to restrict the movement of said first set of centrifugal elements at all speeds below the speed corresponding to the tension in the spring, said last mentioned means comprising a second set of centrifugal elements, and opposing means therefor to permit the radius of gyration thereof to increase with the speed; and a common support for both sets of centrifugal elements, said support being carried by the shaft.

20. In a governor; a shaft; a sleeve slidably mounted thereon; a spring opposing the movement of the sleeve in one direction; means to adjust the tension in the spring; a first set of centrifugal elements opposing the movement in the opposite direction; means to restrict the movement of said first set of centrifugal elements at all speeds below the speed corresponding to the tension in the spring, said last mentioned means comprising a second sleeve on the first sleeve, a second spring intermediate the second sleeve and the first sleeve, and a second set of centrifugal elements associated with the second sleeve to compress the second spring with increase in speed; and a common support for both sets of centrifugal elements, said support being carried by the shaft.

21. In combination, a shaft, a fixed support, a lever pivotally mounted transversely of said shaft, a spring associated with the lever to urge the lever in one direction, means carried on the shaft cooperating with the lever to balance the same and transmit the force to the fixed support, and speed responsive mechanism carried on the shaft and associated with said means to vary the tension in the spring only when the speed exceeds a predetermined amount.

22. In combination, a shaft, a fixed support, a lever pivotally mounted transversely of said shaft, an adjustable spring associated with the lever to variably urge the lever in one direction, means carried on the shaft cooperating with the lever to balance the same and transmit the force to the fixed support, and speed responsive mechanism carried on the shaft and associated with said means to vary the tension in the spring only when the speed exceeds an amount determined by said adjustment.

23. In combination, a shaft, a fixed support, a lever pivotally mounted transversely of said shaft, a helical spring whose axis is parallel with the shaft, associated with the lever to urge the lever in one direction, means carried on the shaft cooperating with the lever to balance the same and transmit the force to the fixed support, and speed responsive mechanism carried on the shaft and associated with said means to vary the tension in the spring only when the speed exceeds a predetermined amount.

24. In combination, a shaft, a fixed support, a lever pivotally mounted transversely of said shaft, a spring associated with the lever to urge it in one direction, means carried on the shaft cooperating with the lever to balance the same and transmit the force to the fixed support, and speed responsive mechanism having a speed-centrifugal force characteristic carried on the shaft and associated with said means to vary the tension in the spring only when the speed exceeds a predetermined amount.

25. In a compound governor; a shaft; a sleeve keyed thereto; two sets of centrifugal elements, one set reacting directly against the sleeve, the other set reacting against the sleeve through a yielding instrumentality, said reactions being in opposite directions; means to support the centrifugal elements and drive them from the shaft; and a yielding instrumentality exerting a thrust on the sleeve, one of the sets of centrifugal elements and one of the yielding instrumentalities constituting a simple governor, the other set of centrifugal elements and the other yielding instrumentality constituting another simple governor, said two governors having different speed-centrifugal force characteristics so interrelated that the forces in the sleeve may be neutralized at one speed.

26. In a compound governor; a shaft; a sleeve keyed thereto; two sets of centrifugal elements, one set reacting directly against the sleeve, the other set reacting against the sleeve through a helical spring which surrounds the sleeve, said reactions being in opposite directions; means to support the centrifugal elements and drive them from the shaft; and a second spring exerting a thrust on the sleeve, one of the sets of centrifugal elements and one of the springs

constituting a simple governor, the other set of centrifugal elements and the other spring constituting another simple governor, said two governors having different speed-centrifugal force characteristics so interrelated that the forces in the sleeve may be neutralized at one speed.

27. In a compound governor; a shaft; a sleeve keyed thereto; two sets of centrifugal elements, one set reacting directly against the sleeve, the other set reacting against the sleeve through a yielding instrumentality, said reactions being in opposite directions; means to support the centrifugal elements and drive them from the shaft; and an adjustable yielding instrumentality exerting a thrust on the sleeve, one of the sets of centrifugal elements and one of the yielding instrumentalities constituting a simple governor having fixed performance, the other set of centrifugal elements and the adjustable yielding instrumentality constituting another simple governor having adjustable performance so interrelated that the forces in the sleeve may be neutralized at a selected speed.

28. In a compound governor; a shaft; a sleeve keyed thereto; two sets of centrifugal elements, one set reacting directly against the sleeve, the other set reacting against the sleeve through a helical spring which surrounds the sleeve, said reactions being in opposite directions; means to support the centrifugal elements and drive them from the shaft; and an adjustable spring exerting a thrust on the sleeve, one of the sets of centrifugal elements and the helical spring constituting a simple governor having a fixed performance, the other set of centrifugal elements and the adjustable spring constituting another simple governor having adjustable performance so interrelated that the forces in the sleeve may be neutralized at a selected speed.

29. In a governor, the combination with a driving shaft, of a speed responsive mechanism associated therewith, said mechanism having a speed-centrifugal force characteristic and including sets of centrifugal elements each supported by the shaft to have a variable radius of gyration, and means to algebraically summate the centrifugal forces developed in the respective sets, whereby the governor is of substantially constant absolute sensitivity at various speeds.

30. In a governor, the combination with a driving shaft, of a speed responsive mechanism associated therewith, said mechanism having a speed-centrifugal force characteristic and including sets of centrifugal elements each supported by the shaft to have a variable radius of gyration, and means to algebraically summate the centrifugal forces developed in the respective sets, and an in-

strumentality responsive to substantially the same increment of speed of the speed responsive mechanism at various speeds.

31. In a governor, the combination with a horizontal driving shaft, of a speed responsive mechanism associated therewith, said mechanism having a speed-centrifugal force characteristic and including sets of centrifugal elements each supported by the shaft to have a variable radius of gyration independent of gravity, and means to algebraically summate the centrifugal forces developed in the respective sets, whereby the governor is of substantially constant absolute sensitivity at various speeds.

32. In a governor, the combination with a driving shaft of a speed responsive mechanism associated therewith, said mechanism having a speed-centrifugal force characteristic and including centrifugal elements supported by the shaft to have a variable radius of gyration, means to algebraically summate the centrifugal forces developed in the respective sets, whereby the governor is of substantially constant absolute sensitivity at various speeds, and stops for the centrifugal elements when at rest.

33. In a governor, a shaft, a plurality of sets of centrifugal elements, a common support for said centrifugal elements carried on said shaft, a member, and means associated with each set of centrifugal elements to impose upon the member in opposite directions the forces developed centrifugally in said centrifugal elements whereby they may be algebraically added, the parts being so arranged as to be susceptible of adjustment while the governor is in operation.

34. In a governor, a shaft, a plurality of sets of centrifugal elements, a common support for said centrifugal elements carried on said shaft, a sleeve carried by the shaft, and means associated with each set of centrifugal elements to impose upon the sleeve in opposite directions the forces developed centrifugally in said centrifugal elements whereby they may be algebraically added, the parts being so arranged as to be susceptible of adjustment while the governor is in operation.

35. In combination, a shaft, a plurality of sets of centrifugal elements, a common support for said centrifugal elements carried on said shaft, a member, means associated with each set of centrifugal elements to impose upon the member in opposite directions the forces developed centrifugally in said centrifugal elements whereby they may be algebraically added, and an instrumentality responsive to the movements of the member caused by unneutralized forces therein, the parts being so arranged as to be susceptible of adjustment while the governor is in operation.

36. In combination, a shaft, a plurality of sets of centrifugal elements, a common support for said centrifugal elements carried on said shaft, a sleeve loosely keyed to said shaft, means associated with each set of centrifugal elements to impose upon the member in opposite directions the forces developed centrifugally in said centrifugal elements whereby they may be algebraically added and the sleeve may slide on the shaft, and a switch responsive to the movements of said sleeve.
